UNITED STATES PATENT OFFICE

ANGUS D. MCKENZIE, OF MANSFIELD, OHIO, ASSIGNOR TO THE AMERICAN SAFETY NAVIGATION COMPANY, OF CANTON, OHIO, A CORPORATION OF OHIO

LOAD-CARRYING AND LAUNCHING DEVICE

Application filed January 20, 1930. Serial No. 421,920.

My invention relates to davits for life boats, and particularly to devices of this character which are gravity operated, and are high slung so as to take up a minimum of 5 deck space. The objects of the invention are to design such apparatus which may be easily operated, which is simple in its mechanical make-up, and which offers the least possibility of being jammed and rendered inoper- 10 ative.

The annexed drawings and the following description set forth in detail certain means embodying my invention, such disclosed means constituting, however, but two of the 15 various forms in which the principle of the invention may be embodied.

In said annexed drawings:

Figure 1 is a side elevation of my improved davit construction, showing the same supporting a life boat, the upright or stationary supporting position of the davit being shown in full lines and a launching position being shown in broken lines;

Figure 2 is a broken side elevation of conventional control mechanism adapted to be utilized with my invention;

Figure 3 is an end elevation of the drums and associated gearing shown in Figure 2;

Figure 4 is a broken front elevation of the 30 parts shown in full lines in Figure 1;

Figure 5 is a fragmentary vertical section, upon an enlarged scale, taken in the plane indicated by the line 5—5, Figure 1;

Figure 6 is a fragmentary plan section, 35 upon an enlarged scale, taken in the planes indicated by the line 6—6, Figure 1;

Figure 7 is a side elevation of a modified type of davit construction in upright stationary supporting position;

Figure 8 is a fragmentary plan view of the 40 elements shown in Figure 7; and

Figure 9 is a front elevation of the construction shown in Figure 7.

Referring to the annexed drawings in 45 which the same parts are indicated by the same respective numbers in the several views, my improved davit construction consists of three main parts, viz., a boom member, a support for carrying the life boat or other load 50 when the latter is in its normal position,

and a cable for raising and lowering the boat. The launching of the load is effected completely by gravity, but controlled by mechanism designed properly to regulate the launching speed.

Referring particularly to Figures 1 to 6, inclusive, in which the invention is illustrated by its application in boat-launching mechanism, upon the ship deck 1 I provide a suitable main support, the latter, for purposes

of illustration in the accompanying drawings, being shown as the frame 2 of a deck house, for instance. This main support 2 is located a suitable distance within the ship rail 3 over which the boat 19 must be launched

when it is desired to lower the same into the water. Upon a pivot pin 5 mounted in the main support 2 adjacent the deck 1 I support a boom member 4 which, as will be plainly seen in Figure 1, is in normal load-carrying

position a substantially vertically-disposed member for the greater part of its length, being sharply curved outwardly at the top toward the rail 3 of the ship, so as to permit the vertical dependency of the life boat 19

from the upper end of the boom member 4, the inner side of the boat 19 lying under the upper curved end of the boom, as will be readily seen and understood. Secured by a pivot pin

7 to the main support 2 in the form of device 70 illustrated, is a depending link 8, the lower end of which is adapted to engage a pin 9 upon which is rotatably mounted a roller 11, the link 8 being formed with an elongated

recess 10 by means of which the pin 9 may 75 move lengthwise of the link 8, the roller 11 during this lengthwise movement riding upon a track member 12 secured to the face of the main support 2. This pin 9 and roller 11 are

carried by one end of a support for carrying 80 the life boat in its elevated normal position, this support being in the form of a bell crank comprised of the two portions 14 and 15 pivoted at their angle point upon a pin 13 secured in the boom 4, the leg 14 being pivotally connected to the link 8 by means of

the pin 9 which is fixedly mounted in the end of leg 14, and the leg 15 contacting the life boat through the medium of shoes 16, 17 and 18 which abut the life boat 19, when the latter

is in its normal raised position, as plainly shown in Figure 1, whereby to steadily and adequately support the life boat.

To any suitable frame member of the life boat 19, such as a seat or block 20 secured substantially midway the width and as high as is practicable and near the end of the boat 19, is attached one end of a cable section 21 by any approved form of hook 60, a block 36 being secured to the other end of said cable section 21 by means of a pin 22. Pin 35 secured adjacent the upper end of this block 36 abuts the surface 37 of the top portion of the boom 4. Secured to pin 35 in one end of a cable 24 which plays over a pair of pulleys 23 and 25 mounted on the boom 4, said cable 24 also playing over a sheave or cable guiding means 26 mounted upon the main support 2 whence the cable 24 passes to a suitable control mechanism 52, Figures 2 and 3, consisting of hoisting apparatus adapted to lower and lift the boat 19 at the desired speed. This control mechanism 52 is common to two launching devices such as has been described, one for each end of the boat 19, the control mechanism being adapted to take in or play out the cables 24 in equal amounts.

No claim is made to any invention in the control mechanism, one conventional form of which is shown in Figures 2 and 3, which includes a motor 53 to whose shaft is fixed a pinion 54 engaging a spur gear 56 secured to one end of shaft 57, and pinion 58 being secured to the opposite end of said shaft 57 and engaging a pair of gears 55 secured respectively to a pair of shafts to which are secured drums 59 upon which the cables 24 are adapted to be wound. Suitable mechanism is thus provided for the desired gear reductions, the paying-out and drawing-in of the cables 24, and other actions necessary in such mechanism.

When the boom 4 has been raised to the upright position it is retained therein through the medium of a latch 28 pivoted at one end upon a pin 27 mounted in the boom 4 and adapted to be secured by a clamp 31 pivoted upon an angle member 30 erected upon the main support 2. This latch 28 is provided with a counterweight 29. When the latch 28 is locked, and the boom has moved outwardly a slight distance, a lower shoulder portion 39 of the latch 28 is adapted to abut a dog 32 secured to the main support 2 and thus prevent the further outward movement of the boom. In order that the boom may not move inwardly, when in this locked position, I provide a clamping bolt 33 intersecting a block 34 mounted between two of the upright angles 30, which bolt 33 can be turned tightly up against the inner face of the boom 4 and thus hold the shoulder member 39 and the locking dog 32 closely in engagement.

The function of the counterweight 29 is to hold the shoulder member 39 on the latch 28

up, so that, during the hoisting operation, this shoulder 39 will not foul and bend the locking dog 32 or cause the latch 28 to be broken. The load on the cable 24 plus the weight of the boom 4 and the boat support 14-15, is more than sufficient to rotate the latch 28, on the pin 27, and to release shoulder 39 from dog 32 during the launching operation, when the latch 31 is pulled off the end of said latch 28 so as to release the latter.

It will be understood that there has thus far been described only one of a pair of duplicate parts forming my entire davit construction, there being provided one of these parts for supporting and operating each end of the boat 19, as suggested in Figure 4, both of these sets of operating elements being controlled through one main hoisting and control apparatus 52 which operates the pair of cables 24.

In the form of device shown in Figures 7, 8, and 9, only one boom structure is utilized, the same being a centrally located device, relative to the boat 41, but constructed and operated substantially along the lines of the device shown in Figures 1, 4, 5 and 6, the changes required being that of widening out the boat support so as to give a sufficient bearing for the life boat, and in providing a spreader at the top end of the boom upon which pulleys may be mounted over which the two cables run, which support the two ends of the boat. Such a single davit construction can be seen in Figure 9 wherein the boat 41 is supported by two cables 42 attached to the boat members 20' which cables 42 play over pulleys 40 hung from the ends of a spreader member 43 mounted adjacent the top of the boom whence the cables 42 pass to and over a pair of pulleys 49 and 50 supported respectively upon the spreader 43 and upon the upright portions of the boom adjacent the top of the latter, whence the cables pass to the sheaves 26 and to the common control mechanism 52. In this form of device in order to provide for the necessary swing of the pulleys 40, when the boom and life boat move outwardly, I mount them in housings 46 which are pivotally hung upon pins 47 mounted in the respective ends of the spreader 43. Similarly to the stop members or means I have provided in the form of the pins 35 in the blocks 36, in the construction shown in Figures 1, 4, 5 and 6, I provide the cables 42 with stop blocks 48, in the construction shown in Figures 7, 8 and 9, which stop blocks 48 are adapted to abut the surfaces 51 of the swinging housing members 46. In this form of device shown in Figures 7, 8 and 9, the boat support 44 is widened out, as plainly shown, and provided with shoes 45 adjacent each end of the boat 41 and upon which the boat rests when in its upper normal position.

In both of the forms of device described,

the boom, when latch 28 is released, tends to rotate outwardly, in a counter-clockwise direction, in the disposition of the parts shown in the accompanying drawings, thus when referring to the form of apparatus shown in Figure 1, causing bearing surface 37 to be held against the pin 35, thus restraining the boom from rotating except as the cables 24 are played out. The load support 15 carries the boat 19 in its normal position. The weight of the boat 19 on the support 15 is carried through the hinge pin 13, thus causing roller 11 to bear against the short rail block 12. When the boom 4 is free to rotate by reason of the release of the latch 28 from the locking lever 31, the load support 14-15 acts as a lever fulcrumed on pin 9. The weight of the lift boat 19 gives a counter-clockwise rotation to the support 14-15 about this fulcrum point 9. Since the pin 13 is mounted in both the boom 4 and the boat support 14-15, it is carried to the left, giving a counter-clockwise rotation to the boom about the pivot pin 5. This movement of the boom 4 increases the distance between the pulleys 25 and 26 until all the slack is taken out of the cable between the surface 37 and the pin 35 by reason of this surface striking against this pin as the boom 4 rotates and moves to the left. The arm 14 of the load support is made considerably shorter than the arm 15, so that the movement of the pivot pin 13 to the left causes the arm 15 to drop rapidly, thus increasing the distance between the bearing surface 37 upon the under side of the top portion of the boom 4 and the support blocks 16 and 17. The cable portion 21 being of fixed length, the load is thus transferred to it. The weight of boom 4 and load-support 14-15 adds to the rotating force in a counter-clockwise direction upon the upper end of the boom 4, when latch 28 is released. The force exerted by the pin 13 upon the boom in a counter-clockwise direction acts at the starting only of the boom rotation, inasmuch as the linkage mechanism controlling the movement of load-support 14-15 causes the load-support to drop away quickly from the under side of the life boat 19.

In order to make certain that pin 35 remains in contact with the surface portion 37 and does not lower vertically relative to the boom 4 until the latter has completed its outward movement, the pulleys 23, 25 and 26 are so located relative to each other and to the pin 5, that the moment arm M-2, Figure 1, is greater than is moment arm M-1. When the cables 24 are restrained from paying out by the hoisting mechanism 52, the weight of the load, after the load support 14-15 has been removed, acts on the moment arm M-2. This is resisted by a force acting on arm M-1. Since arm M-1 is less than arm M-2, the force exerted on the end of arm M-1 must be greater than the weight of

the load acting on arm M-2, if the boom 4 is to remain stationary. Since the cable 24 is free to move on the pulleys except as restrained by pin 35 bearing on the surface 37, this additional force must be applied at this point 37. When the cables 24 are being played out, this internal force continues to hold the pin 35 and the boom surface portion 37 together, and the boom will complete its outward movement before the pin 35 and the surface portion 37 separate. Any location of the pulleys 23, 25 and 26 and pivot point 5 which will cause arm M-2 to be greater than arm M-1 will satisfy these conditions. It is evident that under certain conditions the pulley 25 may not be required. Moment arm M-2 is not constant, but is the horizontal distance between lines drawn vertically from the groove of pulley 23 and the pin 5, so that any list of the vessel will affect arm M-2. A list of the vessel in counter-clockwise direction, in the assembly shown in the accompanying drawings, will increase arm M-2, and therefore, hold pin 35 more tightly against the surface 37, which action, of course, is desirable. A list of the vessel clockwise may decrease arm M-2 until it is less than arm M-1. However, the assembly is such that a launching can be effected against a back list of 30° or more inasmuch as the weight of the boat 19 imposed vertically on the support arm 15 rotates the boom 4 in a counter-clockwise direction until arm M-2 becomes greater than arm M-1, after which the launching action proceeds as if there was no list of the vessel.

Inasmuch as the rotary motion of pin 9 about the pin 13 shortens the distance between the pins 7 and 9, the link 8 is provided with a slot 10 to permit this rotary movement as long as there is any possibility of the load being carried on the support arm 15, after which the link 8 prevents any excessive rotation of the support 14-15. In the broken line position shown in Figure 1, the boom 4 and the load support 14-15 carried thereon have completed their outward movement, this movement having been stopped by the contact of the load-support end 15' with the deck 1.

In the assembly shown, two pulleys 23 and 25 are used in order to obtain the desired lengths of the moment arms M-1 and M-2. Under suitable conditions only one such pulley would be required; whereas, there are probably conditions where even more than two pulleys would be required.

In the design worked out and shown in the accompanying drawings, it is desirable to hinge the load-support 14-15 for three reasons, viz., (1) so that the load-support will drop clear of the life boat 19 and not interfere with the clean cut launching of the latter; (2) so as to multiply the rotating force on the boom at all times and especially

in case of a list in the ship; and (3) so as to cause the end 15' on the load-support arm 15 to be drawn more closely to the pin 5 in order that said load-support and 15' may 5 strike the deck 1, thus acting as a stop for the boom. This stop prevents excessive rotation of the boom in a simple manner. The boom could be stopped by a chain, stop blocks, or other suitable mechanism, where the particular conditions warrant.

10 The proportions of the design worked out and shown in the accompanying drawings require that the support 14—15 move relatively to the boom. However, other proportions 15 would permit this support to be secured rigidly to the boom and still give the desired results and, where the conditions permit, such a fixing of the load-support would be highly desirable. Other conditions 20 might make it desirable to pivot the load-support 14—15 from some fixed part of the vessel, such as the deck housing 2, possibly near the pivot 9 and then control its movement by slides, links, or other mechanism, from a point at or near the pin 13 on the boom. The link 8 produces the desired motion 25 in the support 14—15 in the case worked out and shown and, of course, such motion could be obtained by any number of suitable links, slides, stops, etc.

30 It will be noted from the accompanying drawings that the boat 19 and the launching mechanism are high slung and that a minimum amount of deck space is utilized during the usual non-operating position of the said elements. The counterweight 29, of course, tends to throw the latch 28 out of locking position and it quickly does thus act, to move the latch 28 out of the way, when the locking member 31 is manually lifted. This lifting 35 of the locking member 31 permits the intermediate starting of the outward rotation of the boom and the dropping away of the load-support 14—15 from under the life boat 19, the pin 35 quickly contacting with the under 40 surface 37 of the top end of the boom to stop the boom movement. The action thereafter is controlled by the mechanism 52 controlling the play of the cables 24.

45 What I claim is:

1. A load-carrying and launching device comprising, a main support, a boom pivoted adjacent its lower end to said support and adapted to move outwardly under the force of gravity, a load-support pivoted to the boom and connected by a link to said main support so as to be capable of movement away from the latter, pulleys mounted on the boom, a cable carried over said pulleys and adapted to carry the load during launching, stop means for limiting the upward movement of the cable relative to the boom, said stop means permitting downward movement of the cable at all times, means for controlling the cable movement, and means for

detachably locking the boom in raised position to the main support, the construction being such as to cause said load-support to move away from the supported load during the initial launching movement of the boom.

2. A load-carrying and launching device comprising, a main support, a boom pivoted adjacent its lower end to said support and adapted to move outwardly under the force of gravity, a load-support connected to the boom and connected to said main support so as to be capable of movement away from the latter, pulleys mounted on the boom, a cable carried over said pulleys and adapted to carry the load during launching, means for controlling the cable movement, and means for detachably locking the boom in raised position to the main support, the construction being such as to cause said load-support to move away from the supported load during the initial launching movement of the boom from a normal range of positions of the main support, the load support being positioned in vertical alignment with the load-carrying position of the cable, and the connection of said load support to said boom and main support being such that the load pressure on said load support, if the main support lists inwardly an amount greater than its normal range of positions, causes the boom to rotate outwardly until the normal operative effect obtains.

3. A load-carrying and launching device comprising, a main support, a boom pivoted adjacent its lower end to said support and adapted to move outwardly under the force of gravity, a load-support pivoted to the boom and connected to the main support so as to be capable of movement away from the latter, spaced pulleys mounted on the boom, a sheave mounted on said main support outside the plane passing through said pulleys, a cable carried over said pulleys and sheave and adapted to carry the load substantially during the entire launching movement of the boom, means for controlling the cable movement, the sheave pivot point and said pulleys being so located relative to the pivot point of said boom as to tend to cause an outward rotation of the latter when a load is applied to the cable, and means for detachably locking the boom in raised position to the main support.

4. A load-carrying and launching device comprising, a main support, a boom pivoted adjacent its lower end to said support and adapted to move outwardly under the force of gravity, a load-support secured to said boom, said load-support being pivotally secured relatively to said main support and movable away from the latter, means for controlling the movement of said load-support, a pulley mounted on said boom adjacent the carrying end of the latter, a cable and controlling mechanism therefor, a sec-

on said load-support, control mechanism for actuating said cable, and means for detachably locking the boom in raised position to the main support.

11. A load-carrying and launching device comprising a main support, a boom pivoted near its lower end to said support and adapted to move outwardly under the force of gravity, a load-support pivoted to said boom and connected to said main support, a pulley on the load-carrying end of said boom, a cable carried over said pulley and adapted to carry the load during launching, means for controlling the cable movement, stop means for limiting upward movement of the load relative to said boom, said stop means permitting downward movement of the load at all times, and means for locking said boom in raised position, the construction being such as to cause said load-support to move away from the supported load during the initial launching movement of said boom.

12. A load-carrying and launching device comprising a main support member, a boom member pivoted near its lower end to said support member and adapted to move outwardly under the force of gravity, a load-support pivoted to one of said members and bearing against the other of said members so as to urge said boom member away from said support member when the load bears upon said load-support, a pulley on the load-carrying end of said boom member, a cable carried over said pulley and adapted to carry the load during launching, means for controlling the cable movement, stop means for limiting upward movement of the load relative to said boom member, said stop means permitting downward movement of the load at all times, and means for locking said boom member in raised position, the construction being such as to cause said load-support to move away from the supported load during the initial launching movement of said boom member.

13. A load-carrying and launching device comprising a main support member, a boom member pivoted near its lower end to said support member and adapted to move outwardly under the force of gravity, a load-support pivoted to one of said members, a link connecting said load-support to the other of said members and having a loose connection at one end, a pulley on the load-carrying end of said boom member, a cable carried over said pulley and adapted to carry the load during launching, means for controlling the cable movement, stop means for limiting upward movement of the load relative to said boom member, said stop means permitting downward movement of the load at all times, and means for locking said boom member in raised position, the construction being such as to cause said load-support to move away from the supported load during

the initial launching movement of said boom member.

14. A load-carrying and launching device comprising a main support, a boom pivoted near its lower end to said support and adapted to move outwardly under the force of gravity, a bell-crank pivoted to said boom, one leg of said bell-crank constituting substantially the entire support for the load in its inoperative position and the other leg having a roller bearing against said main support, a pulley on the load-carrying end of said boom, a cable carried over said pulley and adapted to carry the load during launching, means for controlling the cable movement, stop means for limiting upward movement of the load relative to said boom, said stop means permitting downward movement of the load at all times, and means for locking said boom in raised position, the construction being such as to cause said load-support to move away from the supported load during the initial launching movement of said boom.

15. A load-carrying and launching device comprising a main support, a boom pivoted near its lower end to said support and adapted to move outwardly, a load-support adapted to support substantially the entire load in its inoperative position, a pulley mounted on the load-carrying end of said boom, a cable carried over said pulley and adapted to carry the load during launching, means for controlling the cable movement, means for locking said boom in raised position, and stop means for limiting upward movement of said cable relative to said boom, said stop means permitting downward movement of the cable at all times, and said load-support being mounted so that load pressure thereon being it downwardly and causes it to urge the boom outwardly.

16. In a load-carrying and launching device having a boom pivoted near its lower end to a main support for outward movement therefrom, said boom having a pulley near its load-carrying end and a cable carried over said pulley and adapted to carry the load during launching, and means for controlling the cable movement; a load-support comprising a bell-crank, one leg of said bell-crank being provided with portions conforming to the form of the load to be supported, the other leg being shorter than said first-mentioned leg and having a roller at its free end for bearing against said main support, and said bell-crank being adapted to be pivoted to said boom at the angle formed by its two legs.

17. In a load-carrying and launching device having a boom pivoted near its lower end to a main support for outward movement therefrom, said boom having a pulley near its load-carrying end and a cable carried over said pulley and adapted to carry the load during launching, and means for controlling the cable movement; a load-support comprising a

- lever pivoted between its ends to said boom, the portion of said lever to one side of the pivot being adapted to support substantially the entire load in its inoperative position, and the remaining portion of said lever having a link secured thereto for connecting said lever to said main support, the end of said remaining portion being provided with means for rolling contact with said main support.
18. In a load-carrying and launching device having a boom pivoted near its lower end to a main support for outward movement therefrom, said boom having a pulley near its load-carrying end and a cable carried over said pulley and adapted to carry the load during launching, and means for controlling the cable movement; locking means for said boom comprising a dog on said main support, a latch member pivoted on said boom, said latch member having a shoulder adapted to engage said dog and a counterweight adapted to urge said shoulder out of engaging relation with said dog, means for securing said latch member in locking position, and means on said main support for bearing against said boom to maintain said shoulder in close engagement with said dog when said boom is in its raised position.
19. In a load-carrying and launching device having a boom member pivoted near its lower end to a main support member for outward movement therefrom, said boom member having a pulley near its load-carrying end and a cable carried over said pulley and adapted to carry a load during launching, and means for controlling the cable movement; a load-support comprising a bell-crank having legs of unequal length and being adapted to be pivoted to one of said members adjacent the angle formed by its legs, the longer leg being adapted to support the load and the shorter leg being adapted to bear against the other member, whereby the load-support tends to move the boom member outwardly when the load is applied to the longer leg, and the construction of said device being such that the load may act on said longer leg during the initial stages of the launching.
20. A load-carrying and launching device comprising a main support member, a boom member pivoted adjacent its lower end to said support member and adapted to move outwardly under the force of gravity, means for locking said boom member in its inoperative position to said support member, a load-support pivoted to one of said members and adapted to support a load in the inoperative position of said boom member, spaced pulleys on said boom member, a cable-guiding means mounted on said main support member below the plane passing through the axes of said pulleys when said boom member is in its raised position, a cable connected to the load and carried over said pulleys and said guiding means, and means for controlling the movement of said cable, said load-support being movable away from the load and the load being applied to said cable during the initial stages of the launching whereby said cable tends to cause outward movement of said boom member.
21. A load-carrying and launching device comprising a main support, a boom pivoted adjacent its lower end to said support and adapted to move outwardly under the force of gravity, a load-support secured to said boom, said load-support being adapted to support a load when the boom is in its inoperative position and being movable away from the load during the initial launching movement of said boom, a pulley mounted on said boom adjacent its load-carrying end, a cable, mechanism for controlling the movement of said cable and having a cable-guiding means, a second pulley on said boom out of line of and above the plane containing the axis of said first pulley and passing through said guiding means, said cable playing over both said pulleys and said guiding means whereby said cable tends to cause outward movement of said boom when the load is applied to said cable, and a stop member on said cable between the load and said first-mentioned pulley.
- Signed by me this 20th day of December, 1929.
